August Klumpp,
Max J. Progi
His Attorney.

UNITED STATES PATENT OFFICE.

AUGUST KLUMPP, OF MUNICH, GERMANY.

CRATE.

SPECIFICATION forming part of Letters Patent No. 716,247, dated December 16, 1902.

Application filed April 28, 1902. Serial No. 105,073. (No model.)

To all whom it may concern:

Be it known that I, AUGUST KLUMPP, a citizen of Germany, residing at Munich, Bavaria, Germany, have invented certain new and useful Improvements in Crates; and I do hereby declare the following to be a full, clear, and exact description of the invention, such as will enable others skilled in the art to which it appertains to make and use the same.

10 The present invention consists of a spring transporting device for fragile objects, delicate instruments, and the like; and it consists of the details of construction hereinafter set forth, and particularly pointed out in the claims.

15 In order to render the present specification easily intelligible, reference is had to the accompanying drawings, in which similar letters of reference denote similar parts throughout the several views.

20 In Figure 1 a packing case or frame is illustrated suspended by means of four springs, while Fig. 2 shows a frame suspended on two springs. Fig. 3 is a sectional elevation of a 25 modified form of suspension; Fig. 4, a further modification, and Fig. 5 yet another modification, of the spring suspension.

25 *a* is a case or frame in which the instrument or fragile goods are packed or otherwise secured.

30 *b* is the exterior packing case or frame or crate, and to the interior of the same the case or frame *a* is suspended by means of any suitable number of helical or spiral springs *c*.

35 In Fig. 1 four such springs are illustrated, extending from a point close to the corners of the packing case or frame *a* to the interior walls of the exterior case, crate, or frame.

40 In Fig. 3 the springs *c* extend from plates *d*, to which the interior case or frame *a* is pivotally attached at *e*, and nuts *e'* are employed on the said pivots *e*, by means of which the said case may be clamped to the said plates. This device is advantageous in the case of instruments employed in connection with cars and which have to be examined at times and

their indications read off. Thus by loosening the nuts *e'* the instrument may be turned around, the indications read off, and then turned back to its original position and again secured by tightening up the said nuts.

45 In Fig. 4 the exterior frame or case *b* is pivotally supported in a bracket having arms *f* and may be fixed or released in the same by means of a single nut *e'*, as will be readily understood. In Fig. 5 the outer frame or case *b* is suspended in a universal or ball joint *e'* and may be locked to the same by means of the locking-screw *e'*.

50 In all the examples illustrated the instrument or the fragile wares or objects will always be suspended on springs and no jolts or concussions of the outer casing, crate, or case *b* will be imparted to them. In the case of Figs. 3, 4, and 5 the instruments on trains 55 or other cars will also be supported entirely free from vibration.

55 I claim as my invention—

1. In a crate, the combination of inner and outer cases, springs supporting the inner case 70 within but out of contact with the outer case, pivotal supports for one of the cases, and means for locking the case pivotally supported rigidly to the said pivotal supports.

2. In a crate, the combination of inner and outer cases, the inner case pivotally mounted upon a suitable support, the said support suspended by yielding means within and out of contact with the outer case.

3. In a crate, the combination of inner and 80 outer cases, supporting plates within the outer case, springs connecting said plates with the outer case, pivots on the inner case projecting through the supporting plates, and locking-nuts on said pivots to clamp the inner case to the supporting plates.

85 In testimony whereof I affix my signature in presence of two witnesses.

AUGUST KLUMPP.

Witnesses:

ALVESTO S. HOGUE,
AUGUST FUGGER.
